UNITED STATES PATENT OFFICE

156,961

MOTORLESS DRY SHAVER

Rasmus M. Hvid, Wilmette, Ill., assignor to Veed
Corp., Chicago, Ill., a corporation of Illinois

Application November 12, 1947, Serial No. 142,454

Term of patent 14 years

(Cl. D22—3)

To all whom it may concern:

Be it known, that I, Rasmus M. Hvid, a citizen of the United States, residing at Wilmette, in the county of Cook and State of Illinois, have invented a new, original, and ornamental Design for Motorless Dry Shaver, of which the following is a specification, reference being had to the accompanying drawing, forming a part thereof.

Fig. 1 is a side elevational view of a motorless dry shaver embodying my new design;

Fig. 2 is a front elevational view of the motorless dry shaver shown in Fig. 1;

Fig. 3 is a top plan view thereof; and

Fig. 4 is a bottom plan view thereof.

I claim:

The ornamental design for a motorless dry shaver, substantially as shown.

RASMUS M. HVID.
